UNITED STATES PATENT OFFICE.

WILLIAM P. MURPHY, OF WILLOWGLEN, CALIFORNIA.

DESIGN FOR A HOOK.

SPECIFICATION forming part of Design No. 30,609, dated April 25, 1899.

Application filed March 28, 1899. Serial No. 710,830. Term of patent 7 years.

To all whom it may concern:

Be it known that I, WILLIAM P. MURPHY, a citizen of the United States, residing at Willowglen, county of Santa Clara, State of California, have invented and produced a new and original Design for Hooks, of which the following is a specification, reference being had to the accompanying drawing, forming part thereof.

10 The figure is a perspective view showing my new design.

As shown in the drawing, the leading and material feature of the design consists of a triple hook formed of a single wire bent and 15 folded upon itself to form double diverging hooks *a* upon each side of the central bend of the wire. Thence the wires are brought together and form a reverse curve at *b*. The upper ends of the wires are folded or bent

over, lying close together to form a single 20 hook *c*. Thence the wires extend parallel with each other, diverging at the inner ends and bent to form the eyes *d* for the reception of screws, by which the device is fastened to the wall, these eyes being in vertical line 25 above the lower curvature of the part *b*, so that that portion also rests against the wall.

Having described my invention, what I claim as new, and desire to secure by Letters Patent, is—

30 The design for a hook substantially as herein shown and described.

In witness whereof I have hereunto set my hand.

WILLIAM P. MURPHY.

Witnesses:
